VIOLIN RING MUTE

Ingram Cleveland, Oklahoma City, Okla.

Application May 25, 1946, Serial No. 672,317

3 Claims. (Cl. 84—310)

1

The present invention relates to mutes such as are used on and in connection with bridges for stringed musical instruments, and has reference in particular to a novel type ring and mute combined; that is, a ring-mute which may be readily and expeditiously transferred from the bridge to a finger, and vice versa.

Although the mute is susceptible of usage in connection with other types of stringed musical instruments, it is expressly designed and adapted for use in connection with a violin, viola, cello, and double bass, and the drawings, description and claims are to be so interpreted.

Violinists and others using mutes are full well aware of the inconveniences met in employing conventional mutes. Since requirements for utilization of mutes vary according to particular renditions, factors of time and expediency are ever so important to players. Such being the conditions regularly met, I have evolved and produced a simple, dual-purpose unit embodying the prerequisite of both a mute and finger ring, whereby to provide the performer with a mute which may be quickly snapped on the crown of the bridge while in use, and readily detached and worn as a finger ring when not in use.

A mute constructed in accordance with the principles of the instant invention is possessed of the features and advantages so far enumerated and is also desirable because of the combined ornamental and utilitarian characteristics provided.

Other objects, features, and advantages will become more readily apparent from the following description and the accompanying illustrative drawings.

In the drawings, wherein like numerals are employed to designate like parts throughout the views:

Figure 1 is a perspective view of one form or style of ring-mute constructed in accordance with the principles of the instant invention, said figure showing the manner in which the mute is worn as a ring upon a finger.

Figure 2 is an enlarged edge elevational view of the ring-mute shown in Figure 1.

Figure 3 is a rim or side elevation, that is, a view observing Figure 2 in a direction either left or right.

Figure 4 is an edge elevation showing a different embodiment of the ring-mute.

Figure 5 is a marginal or rim elevation observing Figure 4 in a direction from right to left.

Figure 6 is a similar elevational view showing a

2

still further form or embodiment of the invention,

Figure 7 is a view observing Figure 6, for example, in a direction from right to left, and

Figure 8 is a top plan view of Figures 6 and 7.

Inasmuch as the various figures disclose several modifications stemming from the same broad inventive idea, it is advisable, for clearness, to describe each form individually. Figures 1 to 3 will be covered first; then Figures 4 and 5 will be considered, and finally Figures 6 to 8, inclusive.

Reference being had first to Figures 2 and 3, it will be seen that the accessory, as a unit, is referred to as a ring-mute, the same being denoted, as a single article, by the general reference numeral 10. It might be pointed out in this connection that the ring-mute is constructed from suitable material, for example, plastics, wood, or metal, as the case may be. In the form of the invention under advisement, the mute is actually a part of the ring. The ring 11 is in the form of a split band and the free ends of the limbs are bifurcated, as at 12, thus defining furcations 13 which, in turn, constitute the prongs or grips for releasably fitting upon the crown portion of the conventional violin or equivalent bridge (not shown). The intermediate or crown portion of the ring is provided with an ornament 14 which is here shown in the form of a rectangular boss. This may obviously be of varying designs, and, if desired, may be supplemented by the addition thereto of suitable jewels (not shown), this within the discretion of the user.

The ring or band portion is sufficiently resilient to be readily applicable to one's finger, as shown in Figure 1, and if desired the terminals 15 may be bevelled to facilitate application and removal.

In practice, it is clear that the mute may be worn on the finger, as shown in Figure 1, or may be readily detached and applied to the violin bridge (not shown). This makes it possible to shift the ring-mute from the finger to the bridge, and vice versa. Valuable time and inconvenience is saved in the adoption and use of a special mute of the type shown and described.

The same fundamental ideas and results attend the modification shown in Figures 4 and 5, and differentiated by the numeral 16. Here the ring 17 is of the type illustrated and includes inturned extensions or lugs 18 spaced apart to provide the desired opening and closing for use as a ring. The extensions below the ring proper are bifurcated, as at 19, and, again, the bifurcated formations define furcations 20 which constitute

the grips or prongs. The mode of use and application of the ring-mute 16 is the same as the aforementioned ring-mute 10.

Reference is now had to the final modifications seen in Figures 6 to 8, inclusive. Here the principle is basically the same, but the precise construction varies slightly. That is to say, the mute 21 appears as a separate element or part and is formed integral with the central top or crown portion of the split finger ring 22. As 10 brought out in Figure 8, the body of the mute as denoted at 23 is elongated, appearing as a bar, and the T-heads on the opposite ends are fashioned into the prongs. That is to say, the opposite end portions of the respective heads are bifurcated, as at the points 24 and 25, to provide furcations or prongs 26—26 and 27—27, as illustrated. The sets of prongs 26 may be used together or the prongs 27 may be used together, depending upon choice and expediency. It may be said, therefore, that in this form the mute is, in effect, a separate part integrated with the ring and is of a duplex style, the same being built for longevity as well as uniqueness in appearance and design.

The several forms of the invention herein shown and described are exemplary as preferred embodiments of the overall inventive idea. Obviously, many other styles and variations may be adopted and utilized to advantage and with equal facility. It is unnecessary, however, to attempt to picture such species and forms, for the gist of the invention has to do with a single article of manufacture which is so fashioned and made, from suitable material, to function as a ring, on the one hand, and as a mute, on the other. The claims are to be construed with such interpretations in mind.

Ring-type mutes of the form herein shown and described are practical in that they may be made of modern durable plastics such as may be molded to obtain the desired weight, the requisite features of elasticity and the incorporation of colors, if desired, to inject eye appeal where desired.

It is submitted that the construction and designing of the mutes hereinunder advisement embody basic scientific laws of physics and acoustics and serve to filter out disturbing fuzzy and dull nasal-like tones which are so characteristic of many of the types of mutes now on the market. Experience with my mute has shown that it insures a rich mellow quality of tone and resonance so necessary to fine performance. It makes possible a noteworthy advancement in artistic expression and interpretation by bringing out the delicate shading and nuances of the masters, the blending of lights and shadows in full color tones.

The split prongs are so tapered and arranged that they serve to fit snugly on any one of the selected strings between the tail piece and bridge whereby to render the mute, thus suspended, readily accessible.

As before stated the ring portion serves not only as the essential part of the body of the mute as a unit or instrumentality but serves as a convenient means of wearing the mute on the finger of the bow hand as well as a convenient grip when applying or removing the mute from the bridge, making possible a quick smooth transition technique that is virtually imperceptible to the audience and average onlooker.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

20 I claim:

1. As a new article of manufacture, a bridge-type mute for violins and similar members of the stringed musical instrument family comprising a body structure including a split ring having 25 co-acting prong means, the latter being adapted to be detachably mounted on a conventional bridge in usual fashion, said split ring being expandible and contractible for adaptability and adjustability and suitable, if and when desired, 30 to be temporarily worn on the finger of the bow hand of the user.

2. The structure defined in claim 1, wherein the stated prong means is comprised of a pair of complementary prongs forming integral complements of said ring, said prongs having bridge grips, being in spaced parallelism and being spaced from the terminal ends of said split ring.

3. A violin and viola mute of the multiple purpose type illustrated and described comprising a 40 one-piece body embodying a resilient radially expandible and contractible split ring, the terminals of the split end portions of said ring being slightly spaced from each other, and a pair of tangential bridge gripping prongs carried by and forming 45 integral portions of the split end portions of said ring, said prongs being substantially parallel to one another and being circumferentially spaced from said terminals.
